ELECTRIC CIRCUIT BREAKER

William A. Thomas, Plainville, Conn., assignor to General Electric Company, a corporation of New York

Original application August 16, 1950, Serial No. 179,692, now Patent No. 2,627,563, dated February 3, 1953. Divided and this application September 4, 1951, Serial No. 244,897

4 Claims. (Cl. 200—144)

My invention relates particularly to a breaker adapted for use in panel boards or like constructions.

This is a division from application Serial Number 179,692, filed August 16, 1950, now Patent No. 2,627,563, dated February 3, 1953, in which the circuit breaker per se is more fully set forth and claimed.

The above-identified application is directed to a simple and compact breaker which may be operated to open or close a circuit manually and which can be reset manually after automatic opening of the circuit. The circuit breaker is provided with both thermal and magnetic tripping mechanisms to provide for automatic circuit interruption upon the occurrence of continuous overloads of a given value or upon instantaneous overloads of a much higher value.

The present application is directed particularly to the stationary contact and terminal assembly and its mounting with respect to the casing and arc chute.

It is an important object of the present invention to provide an improved structure of this type which facilitates assembly, reduces the cost of manufacture, and provides for plugging in of the circuit breaker to the busses of panel boards or similar equipment.

Further objects and advantages will become apparent from the following description taken in connection with the accompanying drawing in which:

Fig. 1 is a side view of the inside of a circuit breaker embodying my invention showing the parts in closed circuit position and showing an arc chute in cross-section.

Fig. 2 is an edge view partly in section showing the line terminal.

Fig. 3 is a view similar to Fig. 1 showing the parts in the position they occupy when tripped automatically.

Fig. 4 is a view of the right hand edge of the housing showing the load terminal.

Fig. 5 is a fragmentary plan and section on the plane of the line 5—5 of Fig. 3.

Fig. 6 is a view on a smaller scale showing how two of the circuit breakers are mounted on a panel board.

The breaker mechanism is mounted within a rectangular housing formed of insulating material. The two parts of the housing 7 and 7' are secured together by screws or rivets 8, 8, 8. The stationary switch contact 9 is mounted near one edge of the housing and is carried by a lug bent inwardly and downwardly from one end of the main line terminal 10. This terminal consists of a substantially horizontal head plate 11 having spring jaws extending downward from opposite sides and adapted to receive between them a terminal stab or blade S carried by a panel board. To reinforce the spring action of the terminal jaws I may provide a spring clip 10' which embraces the two jaws and biases them into contact position.

The housing is provided with a slot 12 in the lower corner formed by the bottom wall and left-hand end wall or flange 14 to allow for the introduction of a terminal stab as will hereinafter be seen. The edges of the jaws of the terminal 10 abut against the flanges 14 of the housing adjacent the slot 12 and the head of the terminal 10 is cut away to fit the lug 14' which positions the terminal stab in the housing, while the lower ends of the jaws are adjacent the slot in the bottom wall. Above the head of the terminal I provide a barrier plate 15 formed of insulating material and which is positioned by the flange 16 which projects inwardly from the edge wall of the housing. The barrier plate extends across the upper ends of the side walls of the arc chute.

2

The arc chute 18 is formed of suitable fireproof material and it is provided with two substantially parallel rectangular side walls joined by two end walls at right angles to each other, the bottom end wall resting on the bottom flange 19 of the housing part 7, 7'. The upper rear edge 20 of the arc chute extends between the lug and the edges of the contact jaws, with the lug and contact 9 between the side walls of the arc chute, so that the edge 20 is positioned by the contact carrying lug of the terminal 10 while the lower edge of the arc chute is positioned by the lug 21 which projects upwardly from the bottom flange of the housing.

An outlet from the arc chute is provided by the passage 22 which may have restricted sections as shown in Figures 1 and 3 and an outlet or discharge opening 23.

The load terminal 24 may be of suitable form carried by a bracket 25 which is clamped to the housing by a screw 26. The calibrating screw 27 is adjustable in the nut 28 and coacts with a bendable part 29 of the bracket 25.

The thermally responsive bimetallic strip 30 is secured at one end to the bracket 25. A latch member 31 has a pivotal bearing 32 in the housing adjacent the bimetal strip 30. The other end of the latch member 31 has a hook portion 33 which is pressed against the tip of the bimetal strip by a spring 34 which presses against the abutment 35.

The cradle or tripping member 36 has a pivotal bearing 37 in the housing and normally engages the latch 38 of member 31. The movable switch member 39 is hinged in a bearing 40 of the cradle 36 and has a contact 41 adapted to coact with the stationary contact 9.

The actuating lever 42 is hinged or pivoted in a bearing 43 in the housing and provided with a manually operable piece 44 which is adapted to move in a slot 45 in the face of the housing.

Spring 46 connects the upper end of the lever 42 with a lug 47 on the swinging switch member 39.

Normally the spring biases the actuating lever so that its lug 48 presses against the stop shoulder 49 in the housing and the switch member 39 is biased to a closed circuit position.

A flexible low resistance conductor 50 connects the tip of the bimetal member and the movable contact end 41 of the switch member 39.

To manually operate the circuit breaker from the closed circuit position of Figure 1 to an open circuit position it is merely necessary to move the finger piece 44 from the left toward the right whereupon the spring in the conventional toggle action manner will throw the switch member 39 to the right where it will abut against a stop. The contact at the lower end of the switch member is covered by the insulating plate 15 at the upper edge of the arc chute so that the arc in opening the circuit is confined beneath the plate 15 within the chute.

In case of a prolonged small overload above the rated capacity of the breaker the bimetal member 30 will be warped from the position of Figure 1 so that its lower end will engage the hook 33 of the latch 31 and retract the catch 38 from the tip of the tripping cradle 36. When thus released the tripping member will take up the position shown in Figure 3 because of the pull of the spring which thrusts the switch member 39 upwardly and thus tilts the cradle anticlockwise until the cradle abuts against the stop 51 in the housing.

To re-set the circuit breaker the finger piece 44 is moved from the central indicating position of Figure 3 toward the right so that the lug 48 on the actuating lever 42 engages the edge 52 of the tripping cradle and thus causes the tip of the cradle to slide down the catch 38 until the parts are interlocked as shown in Figure 1 with the switch in open circuit position.

By forming the latch member 31 of suitable magnetic material it may serve as an armature effected by the field of a heavy overload passing through the bimetal strip 30 and act to open the circuit in the same manner as above described.

In Figure 6 I have shown two breaker units mounted edge to edge upon a central stab S of the panel board such as shown and claimed in application Serial Number 274,749 filed by William J. Fleming on March 4,

1952, which is a continuation-in-part of application Serial Number 184,759 filed September 14, 1950, assigned to the same assignee as this application.

In such a construction bus bars A, B and C are suitably insulated and mounted within a pan or tray T and each bus bar provided with a terminal stab or blade S. Each edge of the tray is provided with a hook H adapted to interlock with the lug or flange 54 at the edge of the housing opposite the terminal 10. According to such a construction it is possible to greatly reduce the size of the breaker unit and panel board construction.

To mount a breaker unit on a panel board it is merely necessary to engage the edge flange 54 of the housing with a hook at one edge of the panel board and swinging the breaker unit about the hook as a pivot engage the central stab S to provide the desired phase connection. Obviously a breaker unit may be readily detached in the reverse order.

I claim:

1. In a circuit breaker, an insulating housing containing switching mechanism and having a bottom wall, an integral terminal and contact supporting member in said housing comprising a substantially horizontal head plate having cooperating contact jaws extending downward respectively from two opposite sides thereof and having a contact supporting lug extending downward from one end thereof in spaced relation with the edges of said contact jaws, a stationary switch contact on the side of said lug opposite said contact jaws, an arc chute provided with spaced side walls of insulating material joined by at least one end wall extending between said contact jaws and said lug with said lug positioned between said side walls, means for positioning said contact jaws and arc chute in said housing with said jaws adjacent and substantially at right angles to said bottom wall, said bottom wall being provided with an opening communicating with said contact jaws, and said mechanism including a switch member movable between the walls of said arc chute into engagement or disengagement with said stationary contact.

2. In a circuit breaker, an insulating housing containing switching mechanism and having bottom and end walls forming a corner, an integral terminal and contact supporting member in said corner comprising a substantially horizontal rectangular head plate having cooperating contact jaws extending downward respectively from two opposite sides thereof and having a contact supporting lug extending downward from one end thereof in spaced relation with the edges of said contact jaws, a stationary switch contact on the side of said lug opposite said contact jaws, an arc chute made of electrically insulating material provided with substantially parallel spaced side walls joined by two end walls substantially at right angles to each other, one of said walls extending between said contact jaws and said lug with said lug positioned between said side walls, means in said housing for securing said contact jaws and arc chute in said corner of said housing with said jaws adjacent and substantially at right angles to said bottom and end walls, said housing being provided with a slot in said bottom and end walls communicating with said contact jaws, and said mechanism including a switch member movable between the walls of said arc chute into engagement or disengagement with said stationary contact.

3. In a circuit breaker, a two-part rectangular insulating housing containing snap action switching mechanism, an integral terminal and contact supporting member in said housing comprising a substantially horizontal rectangular head plate having cooperating contact jaws extending downward respectively from two opposite sides thereof and having a contact supporting lug extending downward from one end thereof in spaced relation with the edges of said contact jaws, a stationary switch contact on the side of said lug opposite said contact jaws, an arc chute made of electrically insulating material provided with substantially parallel spaced side walls joined by at least one end wall extending between said contact jaws and said lug with said lug positioned between said side walls, projections on said housing parts for securing said contact jaws and arc chute in said housing with said jaws substantially parallel with a side wall of said housing and adjacent a bottom wall of said housing, said bottom wall being provided with an opening communicating with said contact jaws and said mechanism including a switch member movable between the walls of said arc chute into engagement or disengagement with said stationary contact.
4. In a circuit breaker, a two-part rectangular insulating housing containing snap action switching mechanism, an integral terminal and contact supporting member in a lower corner of said housing comprising a substantially horizontal rectangular head plate having cooperating contact jaws extending downward respectively from two opposite sides thereof and having a contact supporting lug extending downward from one end thereof in spaced relation with the edges of said contact jaws, a stationary switch contact on the side of said lug opposite said contact jaws, an arc chute made of electrically insulating material provided with substantially parallel spaced substantially rectangular side walls joined by two end walls substantially at right angles to each other with the remaining two ends open, one of said walls extending between said contact jaws and said lug with said lug positioned between said side walls, projections on said housing parts for securing said contact jaws and arc chute in said lower corner of said housing with said jaws substantially parallel with a side wall of said housing and the end and one edge of said jaws respectively adjacent bottom and end walls of said housing, said housing being provided with a slot in said bottom and end walls communicating with said contact jaws, a barrier of electrically insulating material in said housing positioned above said head plate and extending over the adjacent open end of said arc chute, said housing being provided with an arc discharge opening communicating with the other open end of said arc chute and said mechanism including a switch member pivotally movable between the walls of said arc chute into engagement or disengagement with said stationary contact.
